UNITED STATES PATENT OFFICE.

LOUIS DAVID, OF MONTGOMERY, ALABAMA.

SAWLESS COTTON-GIN.

No. 895,730.

Specification of Letters Patent.

Patented Aug. 11, 1908.

Application filed October 3, 1907. Serial No. 395,746.

To all whom it may concern:

Be it known that I, LOUIS DAVID, a citizen of the United States of America, and resident of Montgomery, county of Montgomery, State of Alabama, have invented certain new and useful Improvements in Sawless Cotton-Gins, of which the following is a full and clear specification, reference being had to the accompanying drawings, in which—

10 Figure 1 is a plan view of my improved ginning floor, the casing of the gin being shown in section; and Fig. 2 is a transverse vertical section thereof.

The present invention is an improvement upon the cotton-gin patented to me February 19, 1907, No. 844,442, in which a horizontal floor composed of a plurality of pairs of small rods having their peripheries in contact in combination with mechanism for rotating 20 adjacent pairs of the rods or shafts alternately in opposite directions, whereby each rod will first coöperate with the rod at one side and then with the rod at the other side, and so on. The disadvantage in this arrangement is that when the direction of rotation of the rods is reversed a portion of the lint that has already been drawn off the seed and passed down through the floor is drawn upwardly again into the hopper or 25 ginning chamber, thus reducing the capacity of the machine.

The object of the present invention is to avoid the return of this ginned lint and I accomplish this by providing means for rotating 30 the adjacent pairs of rods continuously in opposite directions, the alternate rods being of course thereby rotated continuously in the same direction, whereby there will be a constant and uninterrupted stream of lint 35 passing through the floor between the co-acting rods and the returning of the ginned cotton back up through the floor is avoided.

Referring to the drawings by reference characters, *a* designates the rods or shafts 40 composing the ginning floor, these rods being journaled in the frame or casing in any suitable manner and being arranged in a horizontal series and approximately in contact with each other, as in my former patent above referred to. As in my former patent, the al-

ternate rods project beyond the ginning-floor proper for the purpose of receiving a double row of driving gears at each side of the floor, but in the present instance I employ worm-gears *b* instead of plain cog-gears as in my former apparatus. Meshing with each row or series of worm-gears is a long screw *c* extending the full length of the ginning floor and having its ends journaled in the gin frame or casing in any suitable manner, the screws of each pair being respectively right and left screws.

At one end the shaft of each screw is extended and provided with a beveled pinion *d* and meshing with each pair of these pinions is a beveled wheel *e*, carried by a suitable shaft journaled in bearings in the casing and driven in any suitable manner. With this arrangement of gearing it will be observed that the screws of each pair will be driven in opposite directions so that when the screws are turned simultaneously the alternate shafts or rods will all be turned continuously in one direction and the intermediate shafts will all be turned continuously in the opposite direction, thus avoiding the objection I have heretofore pointed out in my former patented machine.

Having thus fully described my invention, what I claim and desire to secure by Letters Patent, is:—

In a cotton-gin, a ginning means consisting of a plurality of pairs of small rods or shafts arranged close together and in parallelism, each rod being provided with a worm-gear at one end, the worm-gears at each side of the gin being arranged in two rows or series, two pairs of worms one at each side of the machine, each worm meshing with one row of worm-gears, and means for continuously and simultaneously rotating the worms of each pair in opposite directions.

In testimony whereof I hereunto affix my signature in the presence of two witnesses this 26 day of September 1907.

LOUIS DAVID.
